Primary Examiner — Darcey E Gottschalk(74) *Attorney, Agent, or Firm* — Rankin, Hill & Clark LLP(57) **CLAIM**

The ornamental design for a wine stopper, as shown and described.

DESCRIPTION

FIG. 1 is a perspective view of a wine stopper according to our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a cross-sectional view taken along line 8-8 of FIG. 6.

The broken lines in the drawings depict portions of the wine stopper that form no part of the claimed design.

1 Claim, 6 Drawing Sheets(56)
